UNITED STATES PATENT OFFICE

149,284

DESIGN FOR AN ELECTRIC HEATER

Joshua Gordon Lippincott, New York, N. Y., assignor to Victor Electric Products, Inc., Cincinnati, Ohio, a corporation of Ohio

Application April 16, 1946, Serial No. 128,641

Term of patent 14 years

(Cl. D81—10)

To all whom it may concern:

Be it known that I, Joshua Gordon Lippincott, a citizen of the United States, residing at New York, in the Borough of Manhattan and State of New York, have invented a new, original, and ornamental Design for an Electric Heater, of which the following is a specification, reference being had to the accompanying drawings, forming a part thereof.

In the drawings,

Figure 1 is a front elevational view of an electric heater, showing my new design.

Figure 2 is a side elevational view thereof.

Figure 3 is a top plan view, as viewed from the top of Figure 2.

Figure 4 is a rear elevational view thereof.

Figure 5 is a top plan view of the base member, having the body of the heater removed therefrom.

Figure 6 is a cross sectional view taken substantially on the line 6—6 of Figure 5.

I claim:

The ornamental design for an electric heater, as shown.

JOSHUA GORDON LIPPINCOTT.
